US00D742220S

(12) **United States Design Patent**
Eyerman et al.

(10) **Patent No.:** US D742,220 S
(45) **Date of Patent:** ** Nov. 3, 2015

(54) **PACKAGING**

- (71) Applicant: **OTTER PRODUCTS, LLC**, Fort Collins, CO (US)
- (72) Inventors: **James V. Eyerman**, Fort Collins, CO (US); **John P. Fitzgerald**, Fort Collins, CO (US); **Christopher J. Melanson**, Fort Collins, CO (US)
- (73) Assignee: **OTTER PRODUCTS, LLC**, Fort Collins, CO (US)
- (**) Term: **14 Years**
- (21) Appl. No.: **29/500,103**
- (22) Filed: **Aug. 21, 2014**
- (51) LOC (10) Cl. **09-03**
- (52) U.S. Cl.
USPC **D9/426**

(57) **CLAIM**

The ornamental design for packaging, as shown and described.

DESCRIPTION

FIG. 1 is a first front isometric view of a packaging showing our new design;

FIG. 2 is a second front isometric view thereof;

FIG. 3 is a first rear isometric view thereof;

FIG. 4 is a second rear isometric view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

The broken lines represent unclaimed subject matter and form no part of the claimed design.
